United States Patent Office

Des. 222,593

Patented Nov. 9, 1971

222,593

VACUUM CLEANER

Charles H. McFarland, Rocky River, Ohio, assignor to
The Scott & Fetzer Company, Lakewood, Ohio

Filed Apr. 1, 1970, Ser. No. 22,194

Term of patent 14 years

Int. Cl. D15—05

U.S. Cl. D49—14

Fig. 3

FIG. 1 is a perspective view of one side of a vacuum cleaner showing my new design.

FIG. 2 shows, in perspective, generally the opposite side of the vacuum cleaner shown in FIG. 1.

FIG. 3 is a rear elevational view of the vacuum cleaner. The broken lines are for illustrative purposes only.

I claim:

The ornamental design for a vacuum cleaner, as shown and described.
